UNITED STATES PATENT OFFICE.

CLINTON C. MURPHY, OF CHICAGO, ILLINOIS.

BUNNING-BOARD SADDLE.

1,133,494.

Specification of Letters Patent. Patented Mar. 30, 1915.

Application filed August 1, 1914. Serial No. 854,503.

To all whom it may concern:

Be it known that I, CLINTON C. MURPHY, a citizen of the United States, and a resident of the city of Chicago, in the county of Cook and State of Illinois, have invented a new and useful Improvement in Running-Board Saddles, of which the following is a specification.

This invention relates to running board 10 saddles for car roofs.

With the usual construction of running board saddles, the ends of the running boards are quite liable to work loose and become dangerous to the trainmen.

15 My invention has for its object to avoid this danger and to provide a running board saddle which will hold the running boards firmly in place and keep them from working loose.

20 The invention consists in a running board saddle having a main member and a separate secondary member, said main member being secured to the car roof, and said secondary member having the running boards 25 securely fastened thereto and being secured to said main member.

In the accompanying drawing, which forms part of this specification, and in which like symbols refer to like parts throughout. 30 Figure 1 is a vertical transverse section of a portion of a car near the ridge, showing a running board saddle embodying the invention applied thereto, said running board saddle being shown in elevation; Fig. 2 is a fragmentary plan view of a car roof showing the running board saddle applied thereto, certain parts being broken away; Fig. 3 is a vertical longitudinal section on the line 3—3 on Fig. 1; and Fig. 4 is a vertical longitudinal section on the line 4—4 on Fig. 1.

40 In the accompanying drawing, the running board saddle is shown applied to a car roof having a ridge pole 1, roof sheathing 2 and outside metal roof sheets 3. The roof sheets 3 extend transversely of the car from the eaves to the ridge. Each roof sheet is provided with an inverted V-shaped flange 4 along each side margin thereof and along the end near the ridge. The side margins of the adjacent roof sheets 3 are spaced apart, and between them a batten 5 is secured to the roof sheathing 2. A side seam cover 6

is supported on each batten 5 and has downwardly projecting hook-shaped flanges 7 which hook under the flanges 4 of the adjacent roof sheets 3. The ends of the corresponding roof sheets 3 near the ridge are spaced apart and the flanges 4 of said roof sheets are hooked under downwardly extending flanges 8 of a ridge seam cover 9. 60

The running board saddle comprises a main member 10 and a plate 11 which is secured to the top of said main member. The main member 10 is preferably a casting. Said main member, in general, comprises a 65 bottom portion 12, which conforms to the pitch of the roof and is adapted to rest upon the side seam covers 6; two upright side portions 13, which support the plate 11; and two hoods or caps 14, which overlap the ends 70 of the ridge seam covers 9. The hoods 14, together with the bottom portion 12 serve the purpose of the well known corner cap. The main member 10 is held in place upon the car roof by a bolt 15 which passes 75 through the center of the bottom portion 12 and through the ridge pole 1.

Extending downwardly from the bottom portion 12 near the longitudinal edges thereof are flanges 16, which engage opposite 80 sides of the side seam covers 6. The bottom portion 12 has in its under face a plurality of recesses 17 which extend transversely thereof. In each of these recesses 17 is fitted a strip 18 of wood, pressed fiber or 85 other non-abrasive material, which projects below the under face of said bottom portion 12 so as to be adapted to bear upon the side seam covers 6.

The side portions 13 of the main member 90 10 have near their ends a flat seat 19, in which there is a bolt hole 20. The running boards 21 are bolted or otherwise securely fastened to the flat plate 11. Said plate 11 has a transverse slot 22 near each end thereof. A bolt 23 passes through each slot 22 of the plate 11 and through the corresponding bolt hole 20 in the flat seat 19 of the main member 10, and clamps said plate securely to said main member 10. Each side 95 portion 13 of the main member 10 is preferably provided with one or more ribs 24 upon which the plate 11 rests.

In using the running board saddle, the

main member 10 of each running board saddle is first secured to the car roof in its proper place by the bolt 15. Next, the running boards 21 are firmly bolted to the plates 11 on the ground or in some other convenient place; and then said plates, together with said running boards, are placed on the main members 10 and securely fastened thereto by the bolts 23. The slots 22 in the plates 11 allow each plate to be fastened to the corresponding main member 10, although said plate and said main member may not exactly aline.

In the construction shown and described, the well-known corner cap is made a part of the running board saddle for the sake of simplicity, strength and cheapness. The running boards, instead of being fastened to the running board saddles while the latter are on the car roof, are fastened to the plates 11, or secondary members, on the ground. Consequently, the fastening between the running boards and the plates 11 can be made very secure, since special fastening machinery may be used, if desired.

The side seam covers 6 are held loosely in place at the ridge and at the eaves of the car, and as the car racks and weaves in service, said seam covers move slightly relative to the roof substructure and at the running board saddles. During such movement of the side seam covers 6, the protecting coating of said seam covers is quite liable to be rubbed off by the running board saddles. In the construction shown and described, the non-abrasive rubbing strips 18 are interposed between the running board saddles and the side seam covers; and, consequently, the rubbing is between said strips 18 and the side seam covers, and the latter are not liable to be injured.

The particular construction of the car roof shown and described forms no part of this invention, and may be other than that shown. Also, the main member 10 of the running board saddle may be made of sheet metal instead of being a casting. Other minor changes may be made in the particular construction of the running board saddle shown and described without departing from my invention; and I do not wish, therefore, to be restricted to the details of that construction.

What I claim as my invention is as follows:

1. In a car, a roof structure, a runway and saddle members for said runway, said saddle members being bolted to the roof structure at the ridge and said runway being detachably secured to said saddle members, the runway comprising transverse metal members having running boards secured thereto by vertical bolts with the nuts on the under side and said metal plates and

said saddle members having registering holes located laterally beyond the running boards, and bolts extending through said holes, whereby the runway may be completed on the ground and applied as a unit to the car.

2. A running board saddle comprising a main member adapted to be secured to a car roof, a separate plate to which the running boards are secured, said plate having a transverse slot near each end thereof, and a bolt passing through each slot and clamping said plate to said main member.

3. A metal running board saddle comprising a main member adapted to be secured to a car roof, rubbing strips of non-abrasive material projecting from the under face of said main member, said rubbing strips being adapted to bear upon the transverse seams of said car roof, a secondary member which is separate from said main member and to which the running boards are secured, and means for fastening said members together.

4. A metal running board saddle comprising a main member having a bottom portion adapted to straddle side seam covers of a car roof, and rubbing strips of non-abrasive material projecting from the under face of said bottom portion and adapted to bear upon said side seam covers.

5. A running board saddle comprising a main member constituting the body portion of said saddle and having a bottom portion, said bottom portion having flanges projecting downwardly therefrom and adapted to engage the opposite sides of the transverse seams of a car roof, a hood integral with said bottom portion and extending outwardly from each side thereof, said bottom portion and said hoods constituting a corner cap for the seams of said roof, said main member being adapted to be secured to a car roof, a separate plate to which the running boards are secured, and means for fastening said plate to said main member, said means being accessible after the running boards are secured to said plate.

6. A metal running board saddle comprising a main member constituting the body portion of said saddle and adapted to be secured to a car roof, said main member having integral therewith a hood projecting from each side thereof and adapted to overlap the ends of the ridge seams of said car roof, a secondary member which is separate from said main member and to which the running boards are secured, and means for fastening said members together said means being accessible after the running boards are secured to said secondary member.

7. A running board saddle comprising a main member constituting the body portion of said saddle and adapted to be secured to

a car roof, a separate secondary member to which the running boards are secured, and means for fastening said secondary member to said main member, said means being accessible after the running boards are secured to said secondary member, said fastening means being capable of coöperating with said secondary member throughout a limited range of adjustment.
